UNITED STATES PATENT OFFICE.

EMANUEL W. SWEIGARD, OF SAN DIEGO, CALIFORNIA.

COMBINATION CHAIR AND STEPLADDER.

Application filed August 18, 1924. Serial No. 732,650.

My invention relates to a combination chair and step-ladder, and the objects of my invention are: first, to provide a combination device of this class which may be used 5 as a chair or a step-ladder as desired, and which may be easily and quickly transformed from one to the other; second, to provide a device of this class which may be easily and quickly transformed into a substantially 10 straight-back kitchen chair, an easy, lounging chair, a sewing or reading chair and the like; third, to provide a device of this class, which, when transformed into a kitchen chair, occupies a relatively small 15 space; fourth, to provide novel means for extending the base of a device of this class when transformed either into a chair or a step-ladder, and also a novel means for varying the inclination of the back and seat 20 when the device is used as a chair, or the step S when used as a step-ladder; fifth, to provide a novel means for varying the inclination of the back when the device is used as a chair; sixth, to provide a novelly 25 constructed, arranged, operated and shiftable foot rest means for a device of this class, which foot rest means may be shifted into a plurality of different positions desired depending upon the use and the comfort of 30 the occupant of the chair; seventh, to provide a novelly constructed table means on the arms of the device when the same is used as a chair; eighth, to provide a novelly constructed means at the upper portion of the 35 device for varying the inclination of the same when used either as a chair or a ladder; ninth, to provide a collapsible platform at the top of the device which serves as a top step when the device is used as a ladder, 40 or when folded downwardly serves as an ornament for the top of the device when the same is used as a chair; tenth, to provide a device of this class which when transformed into a step-ladder is of such a height suitable 45 for any ordinary purposes in or around the house; eleventh, to provide as a whole a novelly constructed combination chair and step-ladder, and twelfth, to provide such a device which is simple and economical of 50 construction proportionate to its functions, very durable, foldable into a compact form so that the same may be readily conveyed from one place to another, which is light of weight, and which will not readily deteriorate or get out of order.

With these and other objects in view, as

will appear hereinafter, my invention consists of certain novel features of construction, combination and arrangement of parts and portions, as will be hereinafter described in detail and particularly set forth in the appended claims, reference being had to the accompanying drawings and to the characters of reference thereon, which form a part of this application, in which:

Figure 1 is a rear elevational view of my combination chair and step-ladder as seen when transformed into a straight-back kitchen chair; Fig. 2 is a side elevational view thereof, showing by dotted lines one of the foot rest members shifted outwardly, and also showing by dotted lines one of the shiftable arms in a downward position with a table member secured thereto; Fig. 3 is a front elevational view thereof; Fig. 4 is another side elevational view of my combination chair and step-ladder transformed into an easy lounging chair with a table member secured to the one arm thereof, showing by dotted lines the foot rest members in variously shifted positions; Fig. 5 is a transverse sectional view of the table member mounted on the one arm of the device, with the section taken through 5-5 of Fig. 4; Fig. 6 is a sectional elevational view of the combination chair and step-ladder transformed into a step-ladder ready for use, with the section taken through the middle thereof, showing certain parts and portions in elevation to facilitate the illustration; Fig. 7 is a perspective view of the collapsible links at either side of the top portion of the device for supporting the platform at the top when the same is used as a step-ladder, and Fig. 8 is a fragmentary enlarged perspective view showing the relation between the lower end of the back member and the seat.

Like characters of reference refer to similar parts and portions throughout the several views of the drawings.

The front leg members 1, upright back members 2, inclined braces 3 and 4, horizontal brace member 5, back seat member 6, back supporting brace member 7, step member 8, rod 9, shiftable rear leg members 10, horizontal braces 11, diagonal braces 12, rod positioning strips 13, screws 14, rod positioning strip brace 15, V-shaped rear leg positioning member 16, staples 17, spring 18, front seat member 19, hinges 20, leg members 21 and 22, cross member 23, step mem-

ber 24, hooks 25, eyes 26, foot rest members 27 and 28, foot rest positioning member 29, step braces 30, back rest member 31, back positioning member 32, spring 33, chair arms 34, chair arm rests 35, chair arm brace members 36, table member 37, top ladder platform 38, hinges 39, collapsible platform brackets 40, and the clips 41, constitute the principal parts and portions of my combination chair and step-ladder structure.

The main side frames of my combination chair and step-ladder consist of inclined front leg members 1 and upright back members 2, preferably secured relatively to each other by means of inclined brace members 3 and 4 at their outer sides and by means of substantially horizontal brace members 5, the back members 2, being staggered, are positioned upwardly relatively to the leg members 1. These side frames, there being two in number, are spaced from and secured relatively to each other by means of a back seat member 6 intermediate the upper and lower ends of the frames at the upper ends of the leg members 1, a back supporting brace member 7 at the upper ends of the upright back members 2, and a step member 8 intermediate the ends of the leg members 1. At the back sides and near the upper ends of each of the back members 2 are provided a plurality of spaced apart, corresponding notches 2^a which are adapted to receive a rod 9 secured at its ends to the upper ends of the shiftable rear leg members 10. These rear leg members 10 are preferably reinforced relatively to each other by means of horizontal cross braces 7 near their upper ends and by means of diagonal braces 12, as shown best in Fig. 1.

The rod 9 at the upper ends of the rear leg members 10 is preferably secured in position in the notches 2^a at the back side of the members 2 by means of the rod positioning strips 13, which are shiftably secured to the back side of the members 2 by means of screws 14 and secured relatively to each other by means of a brace 15 so that the strips 13 may be shifted simultaneously. The holes 13^a through which the screws 14 extend are vertically elongated and provided at their lower ends with enlarged holes 13^b which extend partially therein from the back side of the strip and are adapted to receive the heads of the screws 14. Thus, it will be seen that in order to shift the strips 13 to permit the rod 9 to be positioned in the different notches 2^a, the strips 13 or the brace 15 connecting the same are shifted upwardly and outwardly, spacing the strips from the back side of the members 2, permitting the rod 9 to be positioned in the notches desired. The strips 13 are then shifted inwardly and permitted to drop, thus locking the rod 9 in the notches in which the same is positioned and providing a pivotal connection at the

upper ends of the rear leg members 10 with the upright back members 2 of the main frames.

To limit the backward or forward shifting of the rear leg members 10 about their pivotal connection with the main side frames relatively to said side frames, there is provided a U-shaped rear leg positioning member 16, which is pivotally connected at its sides and near the rear cross portion thereof intermediate the ends of the members 10. The side portions 16^a of the U-shaped member 16 extend forwardly through positioning members, preferably staples, 17, secured to the outer sides and near the upper ends of the inclined braces 4. These side portions 16^a of the member 16 are provided at their lower edges with a plurality of notches 16^b, which are adapted to receive the lower horizontal portions of the staples 17. At the forward ends of the side portions 16^a are provided grip portions 16^c for raising the same at their forward ends and releasing the same from positive engagement with the staples 17. It will be noted that by raising one of the side portions 16^a of the member 16, both guide portions are raised simultaneously by reason of the integral construction of the member 16. To the middle portions of the cross or diagonal braces 12 of the rear leg members 10 is secured the one end of a tension spring 18 which is secured at its opposite end to the cross portion of the member 16, adapted to raise the same at its rear portion and retain the side portions 16^a thereof in positive engagement with the staples 17.

Through the front edge of the back seat member 6 is pivotally connected, by means of hinges 20, the front seat member 19, which is slightly narrower than the member 6. Said seat member 19 is provided at its sides and rear portion with a pair of downwardly extending inclined leg members 21 and at the front portion of its sides with substantially upright leg members 22. These leg members 21 and 22 are secured together and braced relatively to each other at their lower ends by means of a wide cross member 23 which is adapted to rest on the ground or floor when the device is used as a straight-back kitchen chair. The inclined leg members 21 are further braced relatively to each other by means of a step member 24 secured to the leg members 21 intermediate their ends. The rear edges of the inclined leg members 21 are positioned in engagement with the front edges of the inclined front leg members 1 when the device is used as a chair and are locked relatively to each other by means of a hook 25 at the lower end of one of the leg members 1 and an eye 26 at the lower end of one of the leg members 21, as shown best in Fig. 2.

Within the frame formed by the front

upright leg members 22, the front seat member 19 and the leg brace member 23 are foldably positioned the foot rest members 27 and 28. The foot rest member 27 is U-shaped and is pivotally supported at the upper ends of its side members 27^a to near the upper ends of the leg members 22 and is adapted to be shifted forwardly therefrom. To the lower ends of the inner sides and near the 5 rear edges of the side members 27^a of the foot rest member 27 are pivotally connected the lower ends of the side members 29^a of the U-shaped foot rest supporting member 29, as shown best in Figs. 3, 4 and 6 of the 10 drawings. This U-shaped member 29 is adapted to support the free end of the foot rest member 27 in various positions relatively to the main portion of the chair, the foot rest member 27, as shown by solid lines 15 in Fig. 4, being supported in an outward position by the member 29 engaging the corner or step braces 30 secured in the corners between the brace member 23 and the inclined leg members 21. Such brace members 25 30, as described above, are secured in all the lower corners between the inclined leg members 1 and 21 and the several step members to reinforce the structure when the same is used as a step-ladder.

At the upper side and near the rear portion of the rear seat member 6 is secured a 35 back positioning member 32 which is provided with a longitudinal slot 32^a for receiving the lower end of the back rest member 31. This member 31 is positioned at its upper end in engagement with the back supporting brace member 7 and is held in engagement therewith and within the slot 32^a of the member 32 by means of a tension 40 spring 33 secured at its upper end to the back side of the member 31 and at its other end to the seat member 6. The back positioning member 32 is also provided at its front portion with a cutaway portion 32^b 45 into which the lower end of the member 31 may be positioned and retained in said position by the spring 33.

On the outer sides of the inclined braces 3 of the main side frames are pivotally 50 mounted intermediate their ends the chair arms 34, which are adapted, when in downwardly shifted positions, to rest on the chair arm rests 35 secured to the front sides of and intermediate the ends of the braces 3, as 55 shown in Figs. 2 and 4. The normally rear ends of the arms 34 are provided with bifurcated portions 34^a, which are adapted to straddle the chair arm brace members 36 secured near the front portions of the outer 60 sides of the members 2 for stabilizing the chair arms when in a downward position. On the one chair arm 34 is adapted to be removably mounted a table member 37, which is provided at its under side with an angle 65 member 37^a adapted to engage the inner edge and bottom side of the chair arm to retain the table member in position thereon and prevent the same from tilting when bearing upon the same. On the under side of the table member 37 is provided a longitudinally extending strip 37^b which is adapted to engage the outer edge of the chair arm, thus positioning the table member laterally thereon.

At the upper ends of the upright back 70 members 2 is pivotally mounted a platform 38 by means of hinges 39. When the device is used as a step-ladder, as shown in Fig. 6, the platform 38 is shifted to a substantially horizontal position and rests at the forward 75 portion of its under side at the upper ends of the members 2 and the upper edge of the brace member 7. Near the rear edge of the under side of the platform 38 are secured a pair of clips 41, which are pivotally connected by means of collapsible brackets 40 to the members 2. These collapsible brackets consist of pairs of links 40^a and 40^b pivotally connected at their one ends. The links 40^a of each of the brackets are provided 80 with an inwardly bent lug 40^c, which is adapted to be engaged by the end of the link 40^b connected thereto when the bracket is extended, as shown in Fig. 6, the construction of the bracket being shown best in Fig. 7. Thus, it will be seen that there is provided a rigid brace for the platform 38 when the same is shifted to a substantially horizontal position.

It is obvious from this construction, as 85 illustrated in the drawings and disclosed in the foregoing specification, that there is provided a combination chair and step-ladder as aimed at and set forth in the objects of the invention and throughout the specification; and though I have shown and described a particular construction, combination and arrangement of parts and portions of my combination chair and step-ladder, I do not wish to be limited to this particular 90 construction, combination and arrangement, but desire to include in the scope of my invention the construction, combination and arrangement substantially as set forth in the appended claims.

Having thus described my invention, what I claim as new and desire to secure by Letters Patent is:

1. In a device of the class described, a frame provided with a seat member intermediate its ends, a rear leg means pivotally connected to near the upper portion of said frame, means in connection with said frame and said rear leg means for variously pivotally connecting and locking the same relatively to each other, resilient rear leg positioning means in connection with said frame and said rear leg means for simultaneously engaging and disengaging both sides of said frame and said rear leg means from each 100

other intermediate their ends, and another seat member pivotally connected to the front portion of said first mentioned seat member.

2. In a device of the class described, a frame provided with a seat member, a rear leg means shiftably connected relatively to the rear portion thereof, another seat member pivotally connected with the front portion of the seat member of said frame, said

10 last mentioned seat member being provided with downwardly extending portions at its sides, a foot rest member pivotally mounted at its upper portion on the downwardly extending portions of said last mentioned 15 seat member, and another foot rest member pivotally connected near its one end to near the free end of said first mentioned foot rest member, forming a substantially longitudinal extension for the latter.

20 3. In a device of the class described, a frame provided with a seat member intermediate its ends, a rear leg means pivotally connected to near the upper portion of said frame, another seat member pivotally connected to the front portion of said first mentioned seat member, said last mentioned seat member being provided with downwardly extending portions at its sides, a foot rest member pivotally mounted at its upper 25

30 portion on the downwardly extending portions of said last mentioned seat member, and another foot rest member pivotally connected near its one end to near the free end

of said first mentioned foot rest member, forming a substantially longitudinal extension 35 for the latter.

4. In a device of the class described, a frame provided intermediate its upper and lower ends with a seat, a substantially U-shaped foot rest member pivotally supported at the upper ends of its side portions at the under side of said seat near the forward portion thereof and in a manner as to permit said foot rest to be wholly shifted in an out of the way position, and another 40 foot rest member pivotally mounted at its sides near the lower end of said first mentioned foot rest member forming a substantially longitudinal extension for the latter.

5. In a device of the class described, a frame provided with a seat member intermediate its ends, a rear leg means pivotally connected to near the upper portion of said frame, means in connection with said frame and said rear leg means for variously pivotally connecting and locking the same relatively to each other, and resilient rear leg positioning means in connection with said frame and said rear leg means for simultaneously engaging and disengaging both sides 55 of said frame and said rear leg means from each other intermediate their ends.

In testimony whereof, I have hereunto set my hand at San Diego, California, this 8th day of August, 1924.

EMANUEL W. SWEIGARD.
